CLAIM

What is claimed is the ornamental design for a sealable container, as shown and described.

DESCRIPTION

FIG. 1 is a perspective view from beneath a sealable container, showing my new design;

FIG. 2 is a left side view thereof; the right side, front, and rear views are all identical to FIG. 2 and are not shown;

FIG. 3 is an enlarged top view thereof; and,

FIG. 4 is an enlarged bottom view thereof.
